INVENTOR
Casper J. Korndorfer
BY *J. W. Miller*

ATTORNEY

UNITED STATES PATENT OFFICE.

CASPAR J. KORNDORFER, OF RICHMOND BOROUGH, NEW YORK.

CHECK-BOOK.

1,273,874.

Specification of Letters Patent. Patented July 30, 1918.

Application filed September 10, 1917. Serial No. 190,464.

To all whom it may concern:

Be it known that CASPAR J. KORNDORFER, a citizen of the United States, and resident of the borough of Richmond, in the county 5 of Richmond and State of New York, has invented certain new and useful Improvements in Check-Books, of which the following is a specification.

This invention relates to means for preventing the raising of checks and my improvement has particular relation to a combined holder and cutter for checks; whereby, in conjunction with certain printed indications upon the stub portions, the checks may 15 be severed from their stubs in manner to clearly and unchangeably indicate their approximate value.

In brief my invention consists of a frame or holder, having means of attachment to a 20 check book cover, and itself being receptive of a check pad, which may be removably engaged thereby. A transverse cutter is adjustably connected to said frame; and is intended to be pressed against the stub portion 25 of the check while the negotiable portion thereof is being severed. The check stubs employed herewith bear a progressive arrangement of valuation indications, and the check is to be severed at a point in its 30 stub just beyond the indication nearest above the amount for which the check is to be drawn.

Hence the check, when issued, is protected through bearing a marginal indication to 35 the effect that the check value does not exceed a certain amount.

Other features and advantages of my said invention will hereinafter appear.

In the drawings:—

40 Figure 1 is a plan view of a check book with the cover extended open and showing my improved check holder and cutter.

Fig. 2 is a detail perspective view of the check holder and cutter.

45 Fig. 3 is a section through the line 3—3 of Fig. 1, and

Fig. 4 is a section on the line 4—4 of Fig. 2.

I have for example illustrated my invention 50 as applied to a pocket check book, wherein 1 indicates a cover portion, 2 a pad of checks, and 3 a frame or binding device, whereby the pad of checks may be secured to the cover. Said frame may comprise a 55 channel or trough member, having means

for its attachment to the cover, and adapted to receive and tensionally grip the pad of checks, which are inserted therein at the stub end of the pad.

In this manner the check pads may be 60 renewable, while the frame 3 may, if desired, be permanently connected to the cover. I have shown said frame with the opposite end lugs 4, 4, to be entered within slits 5, 5, in the inner surface of the cover, near its 65 rear, fixating portion, as a means of connection.

The frame 3, which lies transversely across the cover, to serve as an end holder or binder for the pad of checks, is provided 70 at one end with a right angular extension or guide rail 6, here shown as lying along the upper edge of the check pad for a portion of the length of the latter.

Said guide rail 6 carries a member 7, here 75 represented as a flat strip of stiff material that lies transversely across the face of the check pad, and is slidably adjustable upon said guide rail, in parallelism with the frame 3. The member 7 has a forward edge 80 8, capable of serving as a cutter to sever checks from the stub portion.

The slidable connection between the member 7 and rail 6 may be effected by forming parallel slits 9 in said member, and fitting 85 said member by said slits upon said rail, which is passed therethrough and over the intervening portion of the rail material.

The checks employed with my improved holder are arranged in pad form, *i. e.*, with 90 their rear edges connected together, to fit *en bloc* within the frame 3.

Each check is provided, over its stub portion, with a series of printed valuation designations, in transverse, parallel lines, the 95 amounts expressed progressing from front to rear of said stub portion. Thus the line of print next the negotiable portion of the check may read "Not over five dollars", the next line "Not over ten dollars", and so on. 100 The purpose is that the negotiable portion of a check, when severed from its stub portion, shall carry with it one or more of these lines of print, the terminal line thereof, next the severed rear edge of the check, indicating the set sum which is next above the amount expressed by the check, as drawn.

Hence, fraudulent raising of the check, thus protected, is rendered nugatory, because the banker would not pay a larger 110

amount than that expressed in the final line of valuation indicated.

It should be particularly observed that with the form of check described, and my improved book and severing means, no additional step is needed, in issuing the check, to protect it.

The adjustable cutter is at hand, and has merely to be moved over the stub portion until its forward edge is at the rear of the valuation line of print. Then the user presses said cutter strip against the pad, with one hand, and with the other hand severs the check.

15 Variations may be resorted to within the spirit and scope of my said invention and parts thereof used without others.

I claim:—

The combination, in a check book having a cover and checks therein whose stub portions bear transversely reading lines of progressive valuation, of a rail mounted on the cover and extending alongside of and transverse to the reading lines, and a check-stub severing cutter slidably carried by said rail, 20 25 said cutter lying lengthwise of said reading lines.

Signed at the borough of Richmond, in the county of Richmond and State of New York this 27th day of August A. D. 1917.

CASPAR J. KORNDORFER.
